(57) **CLAIM**

The ornamental design for an eyeglass and eyeglass components, as shown and described.

DESCRIPTION

FIG. 1 is a front perspective view of the eyeglass and eyeglass components of the present invention;

FIG. 2 is a front elevational view thereof;

FIG. 3 is a rear elevational view thereof;

FIG. 4 is a left-side elevational view of the eyeglass and eyeglass front, the right side elevational view being a mirror image thereof;

FIG. 5 is a top plan view thereof; and,

FIG. 6 is a bottom plan view thereof.

Phantom lining, where utilized, is for illustrative purposes only and is not intended to limit the claimed design to the features shown in phantom.
